UNITED STATES PATENT OFFICE.

CHARLES MORTIMER POTTER, OF NAUGATUCK, CONNECTICUT.

LEVEL.

SPECIFICATION forming part of Letters Patent No. 596,279, dated December 28, 1897.

Application filed April 30, 1897. Serial No. 634,550. (No model.)

To all whom it may concern:

Be it known that I, CHARLES MORTIMER POTTER, a citizen of the United States, residing at Naugatuck, in the county of New Haven 5 and State of Connecticut, have invented certain new and useful Improvements in Levels, of which the following is a full and complete specification, such as will enable those skilled in the art to which it appertains to make and 10 use the same.

This invention relates to levels; and the object thereof is to provide an improved instrument of this class which is simple in construction and operation and by means of which a 15 horizontal line may be quickly and easily found, even when the instrument is placed on an inclined surface.

The invention is fully disclosed in the following specification, of which the accompanying 20 drawings form a part, in which the separate parts of my improvement are designated by the same numerals of reference in each of the views, and in which—

Figure 1 is a side view of my improved level, 25 showing also the method of its operation; Fig. 2, a similar view showing a modified form of construction and the method of its operation; Fig. 3, a partial section on the line 3 3 of Fig. 1; Fig. 4, a plan view of the construction 30 shown in Fig. 3; Fig. 5, a side view of a detail of the construction shown in Fig. 2; Fig. 6, a similar view at right angles to that of Fig. 5; Fig. 7, a side and end view of a supplemental attachment which I employ; Fig. 8, a partial section on the line 8 8 of Fig. 3; Fig. 9, a 35 side view of a modified form of the construction shown in Fig. 5, and Fig. 10 a similar view at right angles thereto.

In the practice of my invention I provide 40 a level which comprises an oblong block 12, and this block may be of the usual form and construction, and in the opposite ends of this block and vertically thereof I form bores or 45 passages 13, which are shown in dotted lines in Fig. 1 and in full lines in Fig. 2, and in these bores or passages are placed metal casings 14, which are angular in cross-section, as shown in Fig. 8, said casings being preferably square in cross-section, and in each of 50 these casings is placed a sliding bar 15, which is also preferably square in form and which is provided with a central longitudinal bore

16, which is screw-threaded, and mounted in the central longitudinal bore of the sliding bar 15 is a screw-threaded shaft 17.

The upper and lower ends of the bores or 55 passages 13 are countersunk, and the lower ends of the casings 14 are flared outwardly, as shown at 18, and the lower ends of the bars 15 are enlarged, as shown at 19.

The upper end of the casing is provided 60 with a flange or rim 20, which is countersunk and bolted to the block 12, and the upper end of the shaft 17 is angular in form and provided with a collar 21, which rests on said flange or rim and is held in place by a plate 22, which is secured to the block and the flange or rim 20 by screws or bolts 23, and mounted on said shaft above the plate 22 is a thumb-nut 24.

The thumb-nut 24 is mounted on the angular portion of the shaft 17, and by turning 65 said thumb-nut said shaft may be turned in the bar 15, and when said thumb-nut is turned in one direction the bar 15 will be projected 70 below the block 12, as shown at the right of Fig. 1. It will be understood that this construction is exactly the same at both ends of the block 12, and each of the bars 15 is provided with a scale, as shown at 25, at the right-hand side of Figs. 1 and 2.

In Fig. 1 I have shown at 26 a portion of a beam or timber, which is provided with an upwardly-directed shoulder or extension 27, and by means of this construction I am enabled 85 to show the method of the operation of my improved level, and it will be observed that by resting one end of the level on the shoulder or projection 27 and by turning the thumb-nut 24 at the opposite end the level may 90 be adjusted so as to find a horizontal line, as will be readily understood, and in Fig. 3 I have shown the beam or timber 26 arranged in an inclined plane, and it will be understood that this beam or timber may represent 95 any inclined surface or structure.

In Fig. 2 I have also shown a modified form of construction, and in this construction I employ all those features of the device hereinbefore described and which are shown in Figs. 1, 3, 4 and 8; but in the form of construction shown in Fig. 2 I provide an attachment for the lower ends of the sliding bars 14, which consists of a screw 28, which is adapted to be

screwed into the lower ends of said sliding bars, and these screws 28 are provided with heads or jaws 29, which are preferably of the form shown in Figs. 5 and 6, and pivotally connected therewith by means of a bolt 30 are blocks or heads 31, provided with side jaws 32, through which the screw or bolt 30 is passed, and the blocks or heads 31 are provided with sharp screws 32, and the screws 32 are secured in a plate or board 33, which is thus made to form a part of the level, which is placed on the inclined surface, and by manipulating one of the thumb-nuts 24 the level may be made to determine or locate a horizontal line, as hereinbefore described.

It will be observed that while the blocks or heads 29 are rigidly secured in the sliding bars 15 the blocks or heads 31 are pivotally connected with the blocks or heads 29, and by means of this construction the device may be made to operate, as will be readily understood.

In Figs. 9 and 10 I have shown another form of the attachment shown in Figs. 5 and 6, and in this form of construction the screws 32 are connected with a block or head composed of plates or jaws 35, the upper ends of which are mounted on the pivot-pin 30 and are bolted together centrally, as shown at 36, and the screws 32 are provided with a cross-head 37, 30 which fits between the plates or jaws 35, through which is passed a pivot pin or bolt 38, and the screws 32 are therefore free to swing between the plates or jaws 35.

It will be understood that this device may be connected with the lower ends of the sliding bars 15, as hereinbefore described with reference to the construction shown in Figs. 5 and 6, and in Fig. 7 I have shown another modification or attachment, by means of 40 which the sliding bars 15, when used as shown in Fig. 1, may be lengthened. This attachment consists of a shaft 39, which is preferably angular in cross-section, and provided at its upper end with a screw 40 and at its lower end with a foot 41, which is also provided with a screw-threaded bore 42, and this attachment may be connected with either or both of the sliding bars 15 by means of the screw 40, and either of the attachments 45 shown in Figs. 5 and 6 or 9 and 10 may be connected with the lower end thereof.

My improved level is simple in construction and operation and is perfectly adapted to accomplish the result for which it is in-

tended, and it is apparent that changes in 55 and modifications of the construction herein described may be made without departing from the spirit of my invention or sacrificing its advantages.

Having fully described my invention, I 60 claim as new and desire to secure by Letters Patent—

1. A level which is provided at each end with a sliding bar which is passed vertically therethrough, each of said sliding bars being 65 provided with a screw-threaded central bore, and with a screw-threaded shaft which is passed thereinto from the upper end thereof, and means for operating said screw-threaded shaft so that the sliding bars may be projected below the bottom of the level, said sliding bar being angular in cross-section and being mounted in casings which are secured in said level, and said sliding bars being also provided with scales which are formed 75 thereon, and the lower ends thereof, being provided with attachments with which are pivotally connected blocks or heads provided with screws, substantially as shown and described.

2. A level which is provided at each end with a sliding bar which is passed vertically therethrough each of said sliding bars being provided with a screw-threaded central bore, and with a screw-threaded shaft which is 85 passed thereinto from the upper end thereof, and means for operating said screw-threaded shaft so that the sliding bars may be projected below the bottom of the level, said sliding bars being angular in cross-section 90 and being mounted in casings which are secured in said level, and said sliding bars being also provided with scales which are formed thereon, and the lower ends thereof, being provided with attachments with which are 95 pivotally connected blocks or heads provided with screws, and a plate or board which is connected with the level by means of said screws, substantially as shown and described.

In testimony that I claim the foregoing as 100 my invention I have signed my name, in presence of the subscribing witnesses, this 26th day of April, 1897.

CHARLES MORTIMER POTTER.
